UNITED STATES PATENT OFFICE.

CHARLES A. ANDERSON AND SAMUEL TREPP, OF EAST ORANGE, NEW JERSEY.

PENCIL-HOLDER.

1,130,696.

Specification of Letters Patent.

Patented Mar. 9, 1915.

Application filed April 18, 1914. Serial No. 332,673.

To all whom it may concern:

Be it known that we, CHARLES A. ANDERSON and SAMUEL TREPP, both citizens of the United States, and residing in East Orange, 5 in the county of Essex and State of New Jersey, have invented certain new and useful Improvements in Pencil-Holders, of which the following is a specification, reference being had to the accompanying drawing, forming a part thereof.

Our invention relates to that class of lead or crayon pencil-holders wherein the lead is projected from its casing when in use and is retracted into the casing when not in use by 15 means of a screw mechanism combined with means for automatically expelling the stub end of the lead or crayon when used up or broken off so that a fresh lead may be inserted in position for use.

Figure 1 is a sectional view of our pencil-holder embodying our invention; Fig. 2 is a side view partly in section of the cap and interior parts other than the casing; Fig. 3 is an enlarged cross-sectional view taken on 25 the line 3—3 of Fig. 2 looking in the direction of the arrow; Fig. 4 is a sectional view of the modification, and Fig. 5 is a detail view of such modification partly in cross section.

Like numerals refer to like parts in the several figures.

Referring to the figures, 6 is the casing of our pencil-holder provided with a threaded bore 7.

8 is a tube, having a longitudinal slot, secured to the cap 9 and adapted to telescope within the casing 6. The casing 6 and cap 9 are rotatably held together, as shown in Fig. 1, by means of a ring 10 contained 40 within the annular recess 11 formed in the cap 9, and bead 12 formed in casing 6, which insures a compact fit between casing and cap and enables them to be rotated one on the other.

13 is the lead or crayon carrier, tubular in form, and having affixed thereto the stud 14, which is adapted to pass through and operate along the slotted tube 8, as shown in Figs. 2 and 3. The carrier 13 holds within 50 it the lead or crayon 15, as shown in Fig. 2, and such lead or crayon is advanced or retracted as the stud 14 passes through the threaded bore 7 when the cap 9 is rotated in one direction or the other. 16 is a pin 55 secured to the cap 9 and fitting within the slotted tube 8 concentrically as shown in

Figs. 2 and 4, and is so located that when the carrier 13 is retracted to the point of the pin 16, further retraction of the carrier 13 will cause the pin 16 to project through the tubular bore of the carrier 13 thereby expelling the stub end of the lead 15 held in such carrier. This enables the carrier 13 to be free to have a fresh lead or crayon inserted therein.

Referring to the modification shown in Figs. 4 and 5, the casing 6 is secured to the cap 9 which supports the pin 16 as in Figs. 1 and 2. However, in the modification the slotted tube 8 is affixed to the point cap 17, 60 as shown in Fig. 5, which is rotatably secured to the casing 6 by the ring 10, located in the annular recess 11 and bead 12 as in Figs. 1 and 2. The lead carrier 13 with its stud 14 is constructed in the same manner 65 as shown in Figs. 1, 2, and 3, and it is evident that the turning of the point cap 17 in one direction or the other will cause the lead 15 to advance from, or to be retracted within, the casing in the same manner as in the preferred embodiment. A further retraction of the lead carrier 13, causing the pin 16 to project into the tubular bore and said carrier, as in the preferred embodiment, 70 will expel the stub of the lead 15 from such 75 carrier.

The pencil-holder so shown and described by us is exceedingly simple in construction, efficient in operation and is effective in advancing or retracting the lead as well as in 80 expelling the stub end when such lead becomes worn off or broken.

What we claim as new is:

1. A pencil-holder comprising a cylindrical casing having a threaded bore, a cap 95 mounted to rotate horizontally on one end of the casing, a slotted tube telescoped wholly within the casing having one end affixed to said cap and the other end free within the casing, a tubular lead carrier, 100 open at both ends, longitudinally movable within the slotted tube, means engaging said carrier and said threaded bore to advance or retract said carrier, and a pin affixed to said cap to expel the lead from the 105 carrier when the latter is retracted against the pin.

2. A pencil-holder comprising a cylindrical casing having a threaded bore, a cap mounted to rotate horizontally on one end of the casing, a slotted tube telescoped wholly within the casing having one end af- 110

fixed to said cap and the other end free within the casing, a tubular lead carrier, open at both ends, longitudinally movable within the slotted tube, means engaging 5 said carrier and said threaded bore to advance or retract said carrier, and a pin affixed to one end of, and concentrically within, said casing to expel the lead from the

carrier when the latter is retracted against the pin.

CHARLES A. ANDERSON.
SAMUEL TREPP.
